(57) **CLAIM**

The ornamental design for a rechargeable heated eye mask assembly, as shown and described.

DESCRIPTION

FIG. 1 is a front perspective view of a rechargeable heated eye mask assembly shown in my new design in a closed and fully assembled configuration;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof; and,

FIG. 8 is a top perspective view of the rechargeable heated eye mask assembly of FIG. 1; showing my new design in an open and partially assembled configuration in which the rechargeable heating component feature is shown partially inserted into the eye mask.

(Continued)

The broken lines in the drawings illustrate the portions of the rechargeable heated eye mask assembly, which form no part of the claimed design.
